TABLE SIGNAL

Edwin D. Foresman and Christopher Colovos,
Scranton, Pa.

Application July 13, 1942, Serial No. 450,742

3 Claims. (Cl. 177—329)

Our invention relates to table service, and has among its objects and advantages the provision of an improved electrically energized audible and visual signal.

In the accompanying drawings:

Figure 1 is a side view of the invention;

Figure 2 is a top view;

Figure 3 is an end view; and

Figure 4 is a diagrammatic view of an electric circuit.

In the embodiment selected for illustration, we make use of a base 10 mounted on a table top 12 and provided with shallow recesses 14 for salt and pepper cellars 16 and 18 and a sugar bowl 20. Upon the base 10 is mounted a socket 22 for an electric lamp 24.

To the bottom face of the table top 12 is secured a vertical metal plate 26 having a right angular flange 28 provided with an opening for the reception of screws 30 threaded into the table top. A right angular flange 32 is formed at the lower end of the plate 26 to constitute a shelf for dry cells 34. These cells are held on the shelf by means of a band 36 attached to the plate 26 by screws 38.

In Figure 4, the cells or battery 34 is connected with a wire 40 electrically connected with switches 42 incorporated in the base 10 and each having a switch element 44 accessible for manual manipulation. Both switches 42 are electrically connected with the lamp 24. A wire 46 leads from the lamp 24 to a flexible contact 48 secured to an insulating support 50 attached to the plate 26. The contact 48 is engageable with a second contact 52 secured to the support 50 and connected with a wire 54 leading to the source of current 34. A wire 56 electrically connects the source of current 34 with a solenoid 58 having its second wire 60 electrically connected with each of the switches 42. Normally the contact 48 is held out of engagement with the contact 52 through the medium of an armature 62 actuated by the solenoid 58. An opening may be provided in the table top 12 to accommodate the wires 40, 46 and 60.

In Figure 1, a link 64 connects the armature 62 with a bar 66 pivotally mounted intermediate its ends on a supporting bolt 68 attached to the plate 26. One end of a tension spring 70 is attached to the link end of the bar 66 and is anchored to a bolt 72 attached to the plate 26. Thus the spring 70 maintains the normal position of Figure 1. To the opposite end of the bar 66 is attached a hammer 74 arranged to strike

a bell 76 attached to a support 78 secured to the plate 26 by a bolt 80.

Upon the bolt 28 is mounted a gear 82 meshing with a pinion 84 attached to a large gear 86, the pinion and this gear being connected as a unit and mounted on a supporting bolt 88. The gear 86 meshes with a pinion 90 fixedly connected with a large gear 92, this pinion and gear being supported on a bolt 94. Both bolts 88 and 94 are anchored to the plate 26. Meshing with the gear 92 is a pinion 96 attached to a fan 98 and rotatably supported on a bolt 100 anchored to the plate 26.

In operation, a customer at the table may 15 secure service by pressing one of the switch elements 44. When either of the switches 42 is closed, the solenoid 58 is energized for pulling the core 62 and pivoting the bar 66 to bring the hammer 74 into engagement with the bell 76. 20 At the same time, movement of the core 62 brings the contact 48 into engagement with the contact 52 for closing the circuit through the lamp 24. As the bar 66 is pivoted by the core 62, a pawl 102 pivoted on the bar moves freely relatively to the gear 82 and then engages with one of the teeth thereon to impart rotation to the gear upon deenergization of the solenoid 58, since the spring 70 returns the lever to its normal position upon such deenergization. While the bell 76 is sounded momentarily, the fan 98 retards rotation of the gear train so that the bar 66 is returned slowly to its normal position. This 25 maintains the contact 48 in engagement with the contact 52 for a considerable period of time to maintain the circuit closed through the lamp 24.

The present invention embodies an audible and visual signal and the mechanism is hidden from view underneath the table top. While the switches 44 are accessible above the table top, the switches are incorporated in the base 10 which constitutes a neat appearing base or mount for the salt and pepper cellars, the sugar bowl and the light. Thus the base 10 is not objectionable so far as appearance is concerned.

Without further elaboration, the foregoing will so fully illustrate our invention, that others may, by applying current knowledge, readily adapt the same for use under various conditions of service.

We claim:

1. In a table top, the combination of a mount on the table top for supporting tableware, a bracket located underneath the table top, a bell mounted on said bracket, a solenoid mounted on said bracket and having an armature, a first switch mounted on said bracket and normally

held in an open position by said armature, a lever pivoted on said bracket and having a hammer engageable with said bell, a rigid link connecting said lever with said armature, a spring acting on said lever to hold the latter in its normal position with the hammer spaced from the bell, a lamp on said mount, an electric circuit connected with said solenoid and said lamp, said first switch being interposed in said electric circuit, switch means incorporated in said mount and connected in said electric circuit, a train of gears mounted on said bracket, a speed governing fan driven by said train of gears, and a pawl connecting the lever with one of the gears, said solenoid being energized through closing of said switch means for moving said armature to close said first switch and pivot the lever to bring said hammer into engagement with said bell, said fan retarding said train of gears to retard opening of said first switch upon deenergization of said solenoid.

2. In an apparatus of the character set forth, an electric lamp, an electric circuit including the lamp, a switch in said circuit tending to assume a closed position to light the lamp, a pivoted lever connected to the switch, a spring connected to the lever normally holding the switch in opened position, electrical means adapted when energized to rock the lever to release the switch for movement into closed position, an electric circuit including said electrical means, a normally 30

opened switch in said second circuit adapted when closed to effect the energization of said electrical means, an audible signal, and means carried by the lever for operating the audible signal when the lever is actuated by said electrical means.

3. In an apparatus of the character set forth, an electric lamp, an electric circuit including the lamp, a switch in said circuit tending to assume a closed position to light the lamp, a pivoted lever connected to the switch, a spring connected to the lever normally holding the switch in opened position, electrical means adapted when energized to rock the lever to release the switch for movement into closed position, an electric circuit including said electrical means, a normally opened switch in said second circuit adapted when closed to effect the energization of said electrical means, an audible signal, means connected to the lever for operating the audible signal when the lever is actuated by said electrical means, the said spring being tensioned when the lever is actuated by said electrical means to effect the opening of said first switch when said electrical means is deenergized by the opening of said second switch, and means for retarding the movement of the lever by the spring when said electrical means is deenergized.
